J. M. WINTROB

LOCKING DEVICE FOR THUMB NUTS

Filed April 10, 1923

INVENTOR

Jacob M. Wintrob

By W. W. Williamson, Mfg.

UNITED STATES PATENT OFFICE.

JACOB M. WINTROB, OF PHILADELPHIA, PENNSYLVANIA.

LOCKING DEVICE FOR THUMB NUTS.

Application filed April 10, 1923. Serial No. 631,109.

To all whom it may concern:

Be it known that I, JACOB M. WINTROB, a citizen of the United States, residing at 918 Pine Street, Philadelphia, in the county of Philadelphia and State of Pennsylvania, have invented new and useful Improvements in a Locking Device for Thumb Nuts, of which the following is a specification.

My invention relates to new and useful improvements in a locking device for thumb nuts, and has for its primary object to provide an exceedingly simple and effective device of this character which forms a prominent part of the thumb nut and which after 10 said thumb nut has been properly adjusted may be positioned so that parts thereof 15 coact with the device on which the thumb nut is mounted to prevent accidental rotation of said thumb nut.

Another object of the invention is to produce as an article of manufacture, a thumb nut having a cap adjustably mounted thereon to control the longitudinal movement of rods which are adapted to register with 25 holes in a device on which the thumb nut is mounted to prevent said thumb nut from being accidentally backed off.

With these ends in view, this invention consists in the details of construction and 30 combination of elements hereinafter set forth and then specifically designated by the claims.

In order that those skilled in the art to which this invention appertains, may understand how to make and use the same, I will 35 describe its construction in detail, referring by numerals to the accompanying drawing forming a part of this application, in which:—

Fig. 1, is a conventional sectional side elevation of an iron illustrating a use for locking the thumb nut embodying my invention.

Fig. 2, is an enlarged fragmentary sectional face view of the device showing the 45 details of construction.

Fig. 3, is a similar view of a slightly modified form of the locking device.

Fig. 4, is a further enlarged end view of 50 one of the rods used in the modified form.

In carrying out my invention as here embodied, I particularly desire to use the locking device in conjunction with a thumb nut to hold the separable members of an electric 55 iron or the like in detachable relation and for convenience of description I have shown

such an iron herein designated by the numeral 2. This iron comprises a base 3 which carries a bolt or screw 4 which registers with a slot 5 in the separable or detachable top 6 the latter being held in place by a thumb 7 threaded onto the projecting end of the bolt 5 engaging the rear beveled end of the detachable top 6.

In that form of the invention illustrated in Fig. 2, the thumb nut has an exteriorly threaded boss 8 on which is screwed the cap 9 carrying a disc 10 which is so mounted in the cap that the latter may rotate independently of said disc and a convenient way of constructing this cap so as to provide the groove 11 for the disc 10 is to utilize a separate ring 12 of less height or length than the height of the side walls of the cap, said ring being swaged or otherwise fixed 60 in the cap and this ring is threaded for engagement with the externally threaded boss 8.

The disc 10 carries a pair of rods 13 which pass through holes 14 in the thumb nut and said rods preferably have enlargements or 65 heads 15 for insertion in the enlarged portions or recesses 16 of the holes 14 and the difference in diameters between the holes and their enlargements provide shoulders which the heads 15 will engage during the 70 outward movement of the cap 9 to limit said outward movement and prevent the cap from being removed from the thumb nut.

When the heads of the rods are projected from the enlarged portions 16 of the holes 75 14 they are adapted to enter aligning holes or pockets 17 formed in the device with which the thumb nut coacts, in this case the top 6 of the iron, after the thumb nut has been properly adjusted upon the screw or bolt 4 having threaded engagement with the threaded bore 18 of the thumb nut.

From the foregoing description it will be seen after the thumb nut has been threaded upon the bolt 4 and to its proper position in engagement with the device 6 the enlarged portions 16 of the holes 14 will be in alignment with the pockets 17. As soon as this adjustment is obtained the cap 9 may be screwed inward on the threaded boss 8 of 80 the thumb nut this carrying the disc 10 toward said thumb nut and causing the rod 13 to be moved longitudinally until their enlarged ends or heads 15 are projected from the recesses 16 into the pockets 17. When 85 the parts are thus positioned the thumb nut will be effectually locked against accidental 90

rotation and therefore the user of a device employing such a thumb nut, as for instance, an electric iron will not be annoyed by the thought that the parts might accidentally become separate.

In Figs. 3 and 4, I have shown a slightly modified form of this invention wherein the cap 19 is slidably or telescopically mounted upon the boss 8 of the thumb nut and to the top wall of this cap are fixed the rods 20 slidably mounted in the holes 14 with the heads 21 of said rods housed in the enlargements or recesses 16 of said holes 14 when the cap is moved outward to the position shown in Fig. 3. The heads 21 of these rods also act to prevent the cap from being withdrawn from the thumb nut in the same manner as set forth in connection with the preferred form of my invention but in this modification the heads of the rods are preferably of oval shape and are slotted laterally as indicated at 22, Fig. 4, to provide a plurality of resilient tongues or elements 23 so as to frictionally engage the side walls of the holes or pockets 17 in the device or article 5 and the tension of said resilient elements or tongues will produce sufficient friction on the side walls of said pockets to prevent the accidental displacement of the cap 19 while permitting said cap to be readily and quickly moved outward when occasion requires.

In this form of the invention after the thumb nut has been properly adjusted on the bolt or screw 4 so that the enlarged portions or recesses of the holes 14 register with the pockets 17 the cap 19 may be readily forced inward so as to move the rods 20 longitudinally and project the heads 21 thereof from the enlargements 16 into the pockets 17 which will effectually lock or hold the thumb nut in place but when it is desired to remove the thumb nut a very slight pull upon the cap will slide it outward and withdraw the resilient heads of the rods from the pockets 17 into the enlarged openings 16 in the thumb nut at which time said nut may be readily revolved for removing the same from the bolt or screw 4.

Of course I do not wish to be limited to the exact details of construction as herein shown as these may be varied within the limits of the appended claims without departing from the spirit of my invention.

Having thus fully described my invention, what I claim as new and useful is:—

1. A locking device for thumb nuts comprising in combination, a thumb nut having a central threaded bore whereby the same may be screwed upon a bolt and further provided with a pair of holes parallel with the bore, each of said holes being of two different diameters, said thumb nut including an externally threaded boss portion, a cap having threaded engagement with said

boss portion and rods actuated by the movements of said cap and passing through the holes in the thumb nut, said rods having enlarged head portions adapted to be projected from the larger portions of the holes as the cap is threaded onto the thumb nut.

2. A locking device for thumb nuts comprising in combination, a device having a pair of holes, a bolt associated with said device, a thumb nut, an integral externally threaded boss formed therewith, said thumb nut and its boss having a threaded bore therethrough for coaction with the bolt, said thumb nut and its boss also having holes therethrough parallel with the bore and so spaced as to align with the holes in the device with which the thumb nut coacts when threaded on the bolt, said holes being of two different diameters to provide shoulders intermediate their length, rods within said holes and having heads fitting the larger portions of the holes and coacting with the shoulders to limit the movements of said rods in one direction and a cap having threaded engagement with the boss of the thumb nut and connected with the rods to control the movements of the latter as said cap is screwed on or off the boss for projecting the heads of the rods into the holes in the device with which the thumb nut is associated or for withdrawing them from such holes.

3. A locking device for thumb nuts comprising in combination, a device having a pair of holes, a bolt associated with said device, a thumb nut, an integral externally threaded boss formed therewith, said thumb nut and its boss having a threaded bore therethrough for coaction with the bolt, said thumb nut and its boss also having holes therethrough parallel with the bore and so spaced as to align with the holes in the device with which the thumb nut coacts when threaded on the bolt, said holes being of two different diameters to provide shoulders intermediate their length, rods within said holes and having heads fitting the larger portions of the holes and coacting with the shoulders to limit the movements of said rods in one direction, a cap, a threaded ring fixed within said cap providing a circumferential groove and a disc within said cap and setting in the groove whereby said cap may be rotated independently of the disc and said disc being fixed to the ends of the rods whereby the latter will be moved in or out of registration with the holes in the device with which the thumb nut coacts as the cap is screwed on or off said thumb nut.

4. A locking device for thumb nuts comprising in combination, a device having a pair of holes, a bolt associated with said device, a thumb nut, an integral boss formed

therewith, said thumb nut and its boss having a threaded bore therethrough for coaction with the bolt, said thumb nut and its boss also having holes therethrough parallel with the bore and so spaced as to align with the holes in the device with which the thumb nut coacts when threaded on the bolt, said holes being of two different diameters to provide shoulders intermediate their

10 length, rods within said holes and having

heads fitting the larger portions of the holes and coacting with the shoulders to limit the movements of said rods in one direction, and a cap coacting with the boss and connected with the rods for moving them longitudinally as the cap is moved on or off the boss of the thumb nut.

In testimony whereof, I have hereunto affixed my signature.

JACOB M. WINTROB.
